UNITED STATES PATENT OFFICE

CHARLES H. DUDLEY, OF HANOVER, NEW HAMPSHIRE

DESIGN FOR A HEAD OF A CANE OR SIMILAR ARTICLE

Application filed April 27, 1932. Serial No. 43,625. Term of patent 14 years.

To all whom it may concern:

Be it known that I, CHARLES H. DUDLEY, a citizen of the United States, residing at Hanover, in the county of Grafton and State of New Hampshire, have invented a new, original, and ornamental Design for a Head of a Cane or Similar Article, of which the following is a specification, reference being had to the accompanying drawing, forming part thereof.

The body of the cane is preferably black and the Indian's face red.

I claim:

The ornamental design for a head of a cane or similar article as shown and described.

CHARLES H. DUDLEY.
